CLAIM

The ornamental design for a mobile device charger with extension stalk, as shown and described.

DESCRIPTION

FIG. 1 is a rear perspective view showing a mobile device charger with extension stalk showing my new design;

FIG. 2 is a front perspective view thereof;

FIG. 3 is a top plan view thereof;

FIG. 4 is a left side view thereof;

FIG. 5 is a front view thereof;

FIG. 6 is a rear view thereof;

FIG. 7 is a right side view thereof; and,

FIG. 8 is a bottom plan view thereof.

The broken lines shown in the drawings depict portions of the mobile device charger with extension stalk or environmental structure and form no part of the claimed design.

1 Claim, 3 Drawing Sheets
